Ellicott City, Md. 21043

Filed Mar. 28, 1972, Ser. No. 239,010

Term of patent 7 years

Int. Cl. D24—01

U.S. Cl. D24—1 B

FIG. 1

FIG. 4

FIG. 2

FIG. 1 is a perspective view of a portable dental stand incorporating my new design;

FIG. 2 is a front elevation thereof;

FIG. 3 is a side elevation thereof; and

FIG. 4 is a top plan view thereof.

The dental instruments have been omitted from FIGS. 1-4 and the support legs are fragmentarily shown in FIG. 3 for ease of illustration.

It is further understood that the undisclosed rear side of the dental stand is planar and has a wood grained surface.

I claim:

The ornamental design of a portable dental stand, as shown and described.
